UNITED STATES PATENT OFFICE.

JOHN J. TOOMEY, OF CHICAGO, ILLINOIS.

OVEN DOOR.

Application filed November 19, 1924. Serial No. 750,810.

To all whom it may concern:

Be it known that I, JOHN J. TOOMEY, a citizen of the United States, residing at Chicago, in the county of Cook and State of Illinois, have invented a new and useful Improvement in Oven Doors, of which the following is a specification.

This invention relates particularly to means for mounting and counterbalancing oven-doors. The invention may be employed very advantageously, for example, in connection with the oven-doors of gas-ranges, or electric ranges.

The primary object is to provide a simple and inexpensive means of mounting and counterbalancing oven-doors in such manner as to render the use of springs and latches unnecessary. When the improved device is employed, the door will remain in either the open or the closed position in which it may be left by the operator.

The invention is illustrated in its preferred embodiment in the accompanying drawings, in which—

Fig. 1 represents a broken elevational view of a range-oven equipped with a counterbalanced door in accordance with the present invention; Fig. 2, a broken sectional view taken as indicated at line 2—2 of Fig. 30—1; Fig. 3, a vertical sectional view taken as indicated at line 3—3 of Fig. 2; Fig. 4, a broken horizontal section taken as indicated at line 4—4 of Fig. 3; and Fig. 5, an inner broken perspective view of one of the lower corners of the oven-door.

In the illustration given, A represents an oven having a front frame A' equipped with a door A². The oven is provided at its sides with the usual air flues, or air spaces, 1.

The oven-door A² may be of any suitable construction. In the form shown, it comprises an outer plate 2 and a lining plate 3. The lining plate usually is of sheet-metal, and the outer plate may be of either cast-metal or of sheet-metal.

The oven-door is equipped at its lower corners with combination hinge and counterbalance members 4. Each member 4 has a flat angular head 4^a which is firmly secured to the outer plate 2 of the door, as by means of screws 5. The lining plate 3 is applied so as to conceal the head 4^a.

Assuming the door to be in the closed position, each member 4 is provided with a rearwardly, or inwardly, extending arm 4^b formed integrally with the head 4^a; and

each arm 4^b is equipped at or near its rear end with an offset member 4^c from which extends an arm 4^d. The portion 4^b of the member 4 is provided with a pivot-perforation 6. The members 4 are made in "rights" and "lefts". The offset arm 4^d, in each case, is adapted to work in the air flue, or air space, 1 at the side of the oven, the laterally extending portion 4^c of the device extending through a perforation, or slot, 7 with which the inner wall 8 of the air space is provided.

The arm 4^d of each member 4 is provided with a series of perforations 9, any one of which may be engaged by a pin, or screw, 10, from which is suspended a counterbalancing weight 11 which is connected with the pin by a wire link 11^a.

It is common to provide in one of the lateral flues of a range a temperature-controlling device, (thermostat) known as a thermolator. Ordinarily, such a device is located in one of the flues adjacent the front wall thereof. The counterbalancing weight 11 can be applied to either one of the combination hinge and counterbalancing members 4; and in practice, the weight 11 will be applied in that flue which does not contain the thermolator.

The door, in the illustration given, is secured to the oven frame A' by means of pintles 12 which engage the pivot perforations 6.

In Fig. 2, the door is shown in full lines in the closed position, and the counterweight 11 is shown in full lines in the corresponding position. The dotted lines represent the open position of the door and the corresponding position of the weight. It will be noted that by reason of the fact that the arms project inwardly, or rearwardly, substantially at right angles to the door, the weight 11 will, when the door is in closed position, be suspended on a long leverage. On the other hand, when the door is moved to the lowered position, the arm which carries the weight is caused to approach the plane of the pivots of the door, and the weight 11 automatically swings to a position close to the plane of the door pivots. In other words, the moment of the weight is decreased when the door is thrown to the lowered position, and is increased when the door is thrown to the standing position. Thus, the weight will effectively hold the door in closed position; and, on the other

hand, when the door is in the lowered position, it will more than counterbalance the weight, so that the door will tend to remain in the lowered position.

5 The improved device is simple, may be cheaply constructed, and is thoroughly effective for its purpose.

It should be added that the counterbalance weight 11 may be shifted so as to vary 10 the counterbalancing action by locating the pin 10 in one or another of the perforations 9, according to requirements. Thus, the same hinge members and weights may serve 15 for doors of different weights and dimensions. The members 4 preferably are provided with stops 13 which are adapted to engage shoulders 14 with which the oven frame is provided, when the oven-door is 20 in the open position indicated by the dotted lines in Fig. 2.

The foregoing detailed description has 25 been given for clearness of understanding only, and no unnecessary limitations should be understood therefrom, but the appended claims should be construed as broadly as permissible, in view of the prior art.

What I regard as new, and desire to secure by Letters Patent, is:

1. In combination, an oven provided at

its sides with air flues and having a front 30 frame, an oven-door, arms rigidly secured to the lower corners of the oven-door and extending inwardly through the door opening, and having their inner end portions offset laterally and disposed in said air flues, 35 pintles connecting said front frame with said arms adjacent their points of attachment to the door, and a weight carried by a link suspended from the offset portion of one of said arms.

2. In combination, an oven-door comprising an outer plate and an inner plate, pivot arms disposed at the lower corners of the oven-door and equipped with heads confined between said plates, said arms being 40 provided adjacent the inner plate with pivot perforations and having offset extremities, an oven provided with lateral flues and with a front frame affording a door-opening through which said arms extend, the offset 45 extremities of said arms being disposed in said flues, pintles supported by said frame and extending into said pivot perforations, and weights adjustably linked to the offset extremities of said arms and depending free- 50 55 ly therefrom.

JOHN J. TOOMEY.
